DESIGN FOR A DENTAL BRUSH

Thorvald H. Mikkelsen, Chicago, Ill.

Application January 2, 1941, Serial No. 97,775

Term of patent 14 years

To all whom it may concern:

Be it known that I, Thorvald H. Mikkelsen, a citizen of the United States and a resident of Chicago, in the county of Cook and State of Illinois, have invented a new, original, and ornamental Design for a Dental Brush, of which the following is a specification, reference being had to the accompanying drawing, forming a part thereof, and in which:

Fig. 1 is a side elevational view of a dental brush showing my new design;

Fig. 2 is an elevational view of the same as seen from above in Fig. 1; and

Fig. 3 is an end view of the same, partly in section as seen from line 3—3 in Fig. 1.

I claim:

The ornamental design for a dental brush, as shown.
